HIS ATTORNEY

UNITED STATES PATENT OFFICE.

WILLIAM A. SMITH, OF ATHENS, PENNSYLVANIA, ASSIGNOR TO INGERSOLL-RAND COMPANY, OF JERSEY CITY, NEW JERSEY, A CORPORATION OF NEW JERSEY.

WATER-TUBE CONNECTION.

Application filed May 20, 1925. Serial No. 31,505.

To all whom it may concern:

Be it known that I, WILLIAM A. SMITH, a citizen of the United States, and a resident of Athens, in the county of Bradford and State of Pennsylvania, have invented a certain Water-Tube Connection, of which the following is a specification, accompanied by drawings.

This invention relates to rock drills of the hammer type, but more particularly to a connection for securing one end of the water tube used to convey water through the drill and the drill steel for the purpose of removing cuttings from the drill hole.

One object of the invention is to enable a water tube to be secured yieldingly in the back head of a rock drill.

Another object is to automatically compensate for wear between the bearing portion of the tube and its seat.

Other objects will be in part obvious and in part pointed out hereinafter.

The invention consists of the combinations of elements, features of construction and arrangement of parts having the general mode of operation substantially as hereinafter described and more particularly pointed out in the appended claims and illustrated in the accompanying drawings, in which,

Figure 1 is a longitudinal view of a rock drill partly in section showing the manner in which the water tube is secured in the back head of the drill,

Figure 2 is an enlarged detailed sectional view of a water tube connection,

Figure 3 is a longitudinal sectional view in perspective of a water plug,

Figure 4 is a longitudinal sectional view in perspective of the plunger, and

Figure 5 is a perspective view of the water plug bushing.

Referring to the drawings and more particularly to Figure 1, the invention is shown embodied in a rock drill in which a cylinder A, a back head B, a front cylinder bushing C, and a front head D are held in operative relation by means of the usual side bolts (not shown). Disposed within the cylinder A is a hammer piston, only the nose E of which is shown, for transmitting blows to a drill steel F supported within the front head D. In this instance, an anvil block G is interposed between the piston nose E and the drill steel F for trans-

mitting blows of the piston to the drill steel. A chuck H is arranged rotatably within the front cylinder bushing C and the front head D and is provided with internal screw threads J at one end to receive a threaded chuck jaw K. The chuck jaw K is provided with inwardly extending lugs L which cooperate with wings O carried by the drill steel to prevent rotation of the drill steel with respect to the chuck jaw K. A chuck key P is disposed within the front end of the front head to limit movement of the steel F in a forwardly direction and is provided with clutch members Q which interlock with corresponding members R of the chuck jaw K to prevent relative rotative movement between the chuck key P and the chuck jaw K. Movement of the drill steel in a rearwardly direction is limited by a chuck bushing H' press fitted into the chuck H and is bored to receive the steel F.

Secured to the cylinder A by means of suitable bolts S is a valve chest T containing a valve (not shown) for distributing the motive fluid to the cylinder. Motive fluid is admitted into the machine through a suitable connection U and the motive fluid is controlled by a throttle valve (not shown) having a controlling lever V.

In accordance with the invention, a water tube W is arranged concentrically through the drill and has a reduced forward end X which extends into the bore of the drill steel F. The tube W is provided with a bulb Y near its rearward end which cooperates with a conical seat Z formed in the back head for preventing leakage of fluid between the bulb and said seat. Suitable means are provided for holding the bulb firmly upon the seat Z and to compensate for any wear which may occur between the bulb and its seat, and to this end, a hollow water plug b is screwed into the back head and is provided at its outer end with flats c to receive a wrench for manipulating said plug. A plunger d having a head e is arranged slidably within a bore f of the plug b and has a bore g to receive the end of the tube W and has a counterbore h at its forward end to bear against the bulb Y for holding said bulb against its seat Z. Movement of the plunger d in a forward direction is preferably limited by means of a bushing j

press fitted into the forward end of the plug. In this instance, the bushing *j* also serves as a guide for the plunger *d*. In order to press the plunger *d* firmly against the bulb *Y*, a spring *k* is arranged within a bore *o* of the plug *b* and bears at one end against the end wall of said bore and with its other end against the head *e* of the plunger. The head *e* of the plunger is countersunk as at *p* to receive the end of the spring.

Cleansing fluid, such as water, is introduced into the machine through a connection *q* secured to the back head *B* in any suitable manner. The connection *q* communicates with the interior of the back head through a passage *r*. The water thus entering the back head is conveyed through a groove *s*, which is in this instance formed longitudinally along the periphery of the plug *b*, and is admitted into the interior of said plug through a hole *t* in the rearward end of the plug and thence through a passage *u* in the plunger *d* and through the tube *Y*. In this instance, the passage *u* forms the restricted portion of the water passage through the back head to the tube and controls the supply of such water to the drill steel.

In order to prevent leakage of fluid from the back head *B*, a water plug cap *v* is screwed on the end of said plug to compress a gasket *w* interposed between it and the back head.

In the operation of the machine, a constant stream of water is caused to flow through the tube *W* and the drill steel *F* for the purpose of cleaning the drill hole so that a clean rock face may always be maintained for the drill steel. The water thus utilized is preferably under a constant pressure, but sufficient pressure is not at all times available for forcing the water and cuttings from the drilled hole, especially in the case of deep hole drilling, and to augment such pressure a certain portion of the actuating fluid is permitted to leak from the front end of the cylinder and through the anvil block *G* into the drill steel. In this way, a puff of air, of sufficient quantity to keep the drill hole clean at all times is obtained during each rearward stroke of the piston. The above described invention has been found to function in an unusually efficient manner and its advantages reside chiefly in the fact that a fluid tight contact will be maintained at all times between the bulb *Y* and its seat *Z* since the spring *k*, by its compressive action may be so adjusted that any wear which

may occur between the contacting surfaces of the bulb and the back head will automatically be taken up.

In many drills in which tubes are employed for the purpose herein described and in which there is no provision made for automatically compensating for wear between the tube and its seat, considerable damage is done to the interior parts of the drill through water entering such parts and washing away the lubricant.

I claim:

1. In a fluid actuated rock drill, the combination of a cylinder with a back head, a conical seat in said back head, a water tube extending through the cylinder, a bulb on said tube, and a spring pressed plunger for holding the bulb in fluid tight contact with the conical seat.

2. In a fluid actuated rock drill, the combination of a cylinder with a back head, a conical seat in said back head, a water tube extending through the cylinder, a bulb near one end of said tube, a plug in said back head, and a spring pressed hollow plunger for holding the bulb in fluid tight contact with the conical seat.

3. In a fluid actuated rock drill, the combination of a cylinder with a back head, a conical seat in said back head, a water tube extending through the cylinder, a bulb near one end of said tube, an adjustable plug in said back head, a hollow plunger slideable in said plug, a spring in the plug to force the plunger against the bulb and forming a fluid tight contact between the bulb and the conical seat, and means for limiting longitudinal movement of the plunger.

4. In a fluid actuated rock drill, the combination of a cylinder with a back head, a conical seat in said back head, a water tube extending through the cylinder, a bulb on said tube, a hollow plunger to receive the end of said tube seating against said bulb, a spring to force the plunger against the bulb for holding said bulb against the conical seat, a plug in the back head to receive the plunger and the spring whereby the tension of said spring may be varied, a bushing in said plug to guide the plunger and limit longitudinal movement thereof in one direction, means for preventing leakage of fluid from the back head, and ports and passages for conveying fluid through the back head to the tube.

In testimony whereof I have signed this specification.

WILLIAM A. SMITH.
